INVENTOR:

W.B. Billings

UNITED STATES PATENT OFFICE.

WILLIAM B. BILLINGS, OF WESTMORELAND, NEW YORK.

COMBINATION COOKER, BAKER, AND BROILER.

SPECIFICATION forming part of Letters Patent No. 268,855, dated December 12, 1882.

Application filed July 17, 1882. (No model.)

To all whom it may concern:

Be it known that I, WILLIAM B. BILLINGS, a citizen of the United States, resident in the town of Westmoreland, county of Oneida, State of New York, have invented a new and useful article called a "Combination Cooker, Baker, and Broiler," of which the following is a specification.

My invention consists in certain improvements upon and additions to a combination baker and boiler for which a patent was granted June 27, 1882, and numbered 260,081.

The following specification sets forth how said improvement is made, the drawings annexed being a part of the specification.

Figures 1 and 2 are front elevation views of my improved baker. Fig. 3 is section view upward of the lower end of the central flue and opening thereof. Fig. 4 is a detached view of the boiler G. Fig. 5 is a similar view of the steamer or box F.

Similar letters represent similar parts in the different views.

Fig. 1 represents my baker, which may be made of Russia iron or other suitable material, and is adapted in size to a three-burner oil-stove, said baker being twenty inches long, thirteen inches wide, and ten inches high, provided with a central flue, *i*, elliptical in form, as in Fig. 3. The size of the baker may be varied to suit a greater or less number of stove-burners. The damper K may be used as shown, or placed in the upper end of the flue. The double top and the double bottoms are shown in Fig. 2, a half-inch space being between them, respectively. The flue *i* extends from the outer bottom to the inner top. The opening L in the outer top, over the central flue, *i*, permits the escape of heat, steam, or gas, and is provided with the rim L', to stiffen the top and to provide a suitable place for broiling meat and for other purposes.

M represents a broiler, of any desired construction, upon the top of the casing and over the central flue. (See Fig. 2.) By the open-

ing *i* in Fig. 2, at the lower end of the central flue, the heat may pass from the burner or any other source of heat between the outer and inner bottoms to the openings *i''*, into the oven D, and through the oven D to the openings *i'''*, passing out between the inner and outer top at L.

In Fig. 1, letter E represents a chamber containing the boiler G and the steamer or box F. These vessels can be made movable or fixed, and when detached the chamber may be used for warming or other culinary purposes. The steamer or box F is made to fit loosely in the boiler G on the rests *ff*, to enable the steam to pass up from the boiler into the top of the steamer or box. The bottom of said steamer being solid, no water drips through it into the boiler. Thus the hot water in the boiler is kept clean and pure for culinary purposes, the water being drawn from the faucet *g*.

Having fully set forth the improvement which produces my combination cooker, baker, and broiler, what I claim as my invention, and desire to secure by Letters Patent, is—

1. A baker provided with double top and double bottom, having openings *i* and *i''* and *i'''*, whereby the air or products of combustion can pass from the burner or any source of heat between the double bottom, then through the oven, and finally through the double top to the opening L, substantially as described.

2. A baker having a central flue, *i*, and damper K, combined with the openings *i*, *i''*, *i'''*, the boiler G, and the steamer or box F, fixed or movable, inclosed in the chamber E, substantially as and for the purposes set forth.

3. A baker having a central flue, *i*, and damper K, the oven D, provided with openings *i*, *i''*, *i'''*, and the chamber E, provided with the boiler G and the steamer or box F, for the purposes substantially as set forth.

W. B. BILLINGS.
